C. E. STRICKLAND

SIGN

Original Filed March 19, 1927

UNITED STATES PATENT OFFICE.

CLARENCE E. STRICKLAND, OF ATLANTIC CITY, NEW JERSEY, ASSIGNOR OF ONE-THIRD TO DAVID S. BROWN AND ONE-THIRD TO EMMA R. DAWSON, BOTH OF ATLANTIC CITY, NEW JERSEY.

SIGN.

Application filed March 19, 1927, Serial No. 176,803. Renewed April 26, 1928.

This invention relates to certain improvements in signs and has relation more particularly to a device of this kind especially designed and adapted for use in street display, and it is an object of the invention to provide a sign of this kind embodying a display member or plate normally maintained in a predetermined position yet which readily yields to the action of the wind whereby 10 toppling over of the device under such action is substantially eliminated.

The invention consists in the details of construction and in the combination and arrangement of the several parts of my improved sign whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawing, wherein:—

Figure 1 is a view in elevation of a sign constructed in accordance with an embodiment of my invention;

Figure 2 is a vertical sectional view taken 30 through the device as illustrated in Figure 1 with certain of the parts in elevation;

Figure 3 is a view in top plan of the device as illustrated in Figure 1 with different positions of the sign member or plate indicated 35 by broken lines;

Figure 4 is a view in bottom plan of the structure as herein set forth.

As herein disclosed, B denotes a base member of requisite dimensions and which has its 40 under surface provided with a relatively large pocket 1, the base wall *a* of which is provided with a recess 2. Extending upwardly from the base B is a tubular standard or column 3, the bore of which being in 45 communication with the recess 2. This standard or column 3 is threaded, as at 4, or otherwise as may be preferred operatively engaged with the base B.

Extending through the standard or column 50 3 is a shaft 5, the lower end portion of which is operatively engaged, as at 6, with a disc 7 housed within the recess 2, and the opposite end portion of the shaft 5, as here-

in disclosed, is provided with an outstanding collar 8 resting upon the upper end of the 55 standard or column 3. The shaft 5 extends a desired distance beyond the collar 8 and engaged with said extended portion 9 is a socket member 10 held to the portion 9 through the instrumentality of the set screw 60 11 or the like. This socket member 10 carries the sign plate or member 12 which may be of any preferred configuration and dimensions but preferably has its flat faces vertically disposed.

65 The disc 7 at a point offset from its center is provided with a depending member 14 to which is suitably secured an extremity of a retractile spring 15 the opposite end portion of which spring is secured to a member 16 70 depending from the base wall *a* of the pocket 1.

The tension of the spring 15 is such to normally maintain the sign plate or member 12 in a fixed position yet readily permit said member or plate 12 to yield to the action of the wind so that the liability of such action 75 toppling over the sign is substantially eliminated.

From the foregoing description it is 80 thought to be obvious that a sign constructed in accordance with my invention is particularly well adapted for use by reason of the convenience and facility with which it may be assembled and operated, and it will also 85 be obvious that my invention is susceptible of some change and modification without departing from the principles and spirit thereof and for this reason I do not wish to be understood as limiting myself to the precise 90 arrangement and formation of the several parts herein shown in carrying out my invention in practice except as hereinafter claimed.

95 I claim:—

A sign comprising, in combination, a fixed part including a tubular standard, a shaft disposed therethrough, a sign plate carried by the shaft, a disc carried by the shaft, and a retractile spring having connection with 100 the disc at a point offset from the shaft and with the fixed part to normally maintain the sign plate in a predetermined position.

In testimony whereof I hereunto affix my signature.

CLARENCE E. STRICKLAND.
